J. J. KIME.
INSERT VALVE FOR BOTTLE NECKS.
APPLICATION FILED MAR. 13, 1913.

1,082,125.

Patented Dec. 23, 1913.

UNITED STATES PATENT OFFICE.

JOHN J. KIME, OF LAGRANGE, INDIANA.

INSERT-VALVE FOR BOTTLE-NECKS.

1,082,125.

Specification of Letters Patent. Patented Dec. 23, 1913.

Application filed March 13, 1913. Serial No. 754,038.

To all whom it may concern:

Be it known that I, JOHN J. KIME, a citizen of the United States, and a resident of Lagrange, county of Lagrange, State of Indiana, have invented certain new and useful Improvements in Insert-Valves for Bottle-Necks, of which the following is a specification.

This invention relates broadly to a valve construction and more specifically to a valve adapted to be inserted in a neck of a bottle.

The principal object of this invention is to provide a valve of simple cheap construction that is adapted to be inserted within 15 a bottle neck to obstruct the filling of the bottle after it has once been emptied.

A further object of this invention is to provide a valve member constructed from tubular material in such manner that the 20 seats for the valve comprise annular spun rings in the tubular member, the valve member being provided with a rigid bar coöperating with resilient arms to prevent the withdrawal of the valve member after it has 25 once been inserted in the bottle neck.

Another object of this invention is to provide an insert valve member carrying a stopper so constructed as to be capable of being inserted in the bottle neck after the 30 bottle is filled and to be rigidly and effectually locked in place, thus preventing the withdrawal of the valve member after it is once inserted in the neck of a bottle.

Other and further objects of this invention will in part be obvious and will in part be pointed out in the specification herein-after following by reference to the accompanying drawings in which like numerals represent like parts throughout the several 40 figures thereof.

Figure 1 is a detail sectional view of one form of the invention showing a double ball valve, the upper valve acting as a barrier to prevent tampering with the lower valve.

Fig. 2 is a perspective view of a form of the invention showing a single ball valve and illustrating in dotted lines the position of the locking parts when the valve insert member is being introduced into a bottle neck.

Fig. 3 is a sectional detail view showing the invention with a single ball valve and a stationary barrier intended to prevent tampering with the valve. Fig. 4 is a detail view showing a cross section of the barrier illustrated in Fig. 3. The detail view in Fig. 4 is taken upon the lines A—A in Fig. 3 looking in the direction of the

arrows. Fig. 5 is a cross section view of the locking bar. This view illustrates the end of the section taken between the lines 60 B—B and C—C in Fig. 3.

In many lines of fluid merchandise it is desirable to have a bottle from which the ordinary contents may be very easily poured, but which is very difficult, or substantially 65 impossible to refill in any ordinary manner. Many types of valves have been invented to accomplish this purpose. For the purpose of analysis in connection with the present invention, these types of valves may 70 be divided into two classes. Those which require a particular and special form of bottle neck entirely different from the usual bottle and which are made or formed in connection with the bottle at the time of 75 its manufacture, and a second class comprising those which are adapted to be inserted in the bottle after it is once made. The present invention relates to the latter class, namely, a type of valve adapted to be 80 inserted in a bottle neck of substantially ordinary construction after the bottle has been filled. The device constituting the present invention carries with it the valve, the ordinary stopper and the parts for locking 85 the member in position in the bottle neck after it is once inserted, thus rendering the operation of introducing this member merely a substitute operation for the operation of corking the ordinary bottle, and this 90 invention has been directed particularly to simplicity and cheapness in cost of manufacture.

Referring more particularly to the drawings, and specifically to Fig. 1, a bottle neck 95 1 is intended to represent merely the ordinary well known type of bottle neck which has been made a sufficient length to accommodate the insert valve member which comprises a tubular body section 2 upon which 100 are spun an upper annular bead 4 and a lower annular bead 5. These beads are adapted to form seats for valve balls 6 and 7 respectively. The wall of the tubular body section is provided with a plurality of indented projections 8 and 9 which limit the movement of the valve balls when the bottle is tipped to unseat the balls from their position on the annular bead valve seats. Unless the projections 9 are provided for the 110 valve ball 7, this valve would seat against the lower portion of the upper annular bead 4, and it would be difficult to pour the contents from the bottle. The upper por-

tion of the tubular body member is spun outwardly to constitute a circular flange 10 which is adapted to fit rather tightly the mouth or chime of the neck 11, and the 5 upper portion of the tubular body section carries an ordinary stopper cork 12. A suitable gasket 14 is adapted to lie within the circumferential groove formed in spinning the lower annular bead 5. This gasket eff- 10 fectually prevents the passage of any fluid between the bottle neck and the tubular member. Attached to the lower end of the tubular member are two spring arms 15 and 16. The spring arms 15 and 16 are 15 curved in such manner that a portion of these arms substantially conforms to the interior curvature of the bottle where the neck joins the body portion of the bottle. This curvature of the arms causes them to 20 exert a pressure against the bottle to draw the flange 10 tightly against the chime 11 of the bottle neck. This curvature also has a further advantage in that it permits the device to adjust itself to such irregularities 25 in the length of the neck as ordinarily occur in the manufacture of bottles. If the material from which the tubular member is formed is sufficiently resilient, it is preferred that these spring arms be formed in 30 a tegular with the body portion, but if circumstances require the tubular body portion to be made of such material as is not sufficiently resilient, then it is desirable that the arms be formed of separate pieces and at- 35 tached to the body portion. These arms normally exert a pressure against the bottle neck when the device has been inserted therein, thus tending to draw the flange 10 tightly against the chime of the neck.

40 In order to prevent withdrawal of the valve from the neck, the arm 15 carries a rigid locking bar 17, which is illustrated as being formed by folding the metal over the edges, as is shown in Figs. 2 and 5. This 45 rigid locking bar is adapted to assume the position indicated in dotted lines in Fig. 2 when the tubular valve member is being inserted in the bottle neck, and immediately as the device is completely inserted in the 50 neck the spring arms 15 and 16 diverge permitting the rigid locking bar 17 to be snapped into engagement with a stop 18 formed by the end of the spring arm 16. The stop 18 is formed adjacent a retaining 55 notch 19, with which the locking bar 17 engages if there is any attempt made to withdraw the tubular member from the bottle neck. It will be noted that the locking bar lies at right angles to the axis of the 60 bottle neck, and since the locking bar is a positive rigid bar that assumes this trans- verse position when the tubular member is inserted in the neck, this bar is a positive

absolute barrier preventing removal of the device from the bottle neck.

65

Referring now more particularly to Figs. 3 and 4, these figures illustrate a type of barrier used in connection with the ball valve to prevent insertion of wires or any such means to disturb the valve whereby it might be possible to refill the bottle by lifting the valve from the seat. The barrier illustrated comprises a solid cylindrical wall 20 which is held in position in the tubular body member by means of rings 21 that are spun in the tubular body member. The cylindrical wall 20 is provided with two openings 22 and 24 extending in the direction of the bottle neck. The opening 22 extends from the upper surface of the barrier 75 downwardly almost through the wall. The opening 24 is substantially parallel to the opening 22, but the opening 24 extends upwardly from the under surface nearly through the cylindrical wall. Transverse 80 openings 25 and 26 intersect the openings 22 and 24 respectively, at substantially right angles, intermediate the ends of the openings in such manner as to leave a pocket extending below the point of intersection. A 85 transverse connector opening 27 intersects the transverse openings 25 and 26 at substantially right angles and intermediate the ends of the said transverse openings.

90

It will be noted that the openings in the barrier comprise a pair of parallel vertical conduits or openings, intersected by a pair of horizontal or transverse conduits or openings, which in turn are finally connected by a single connecting transverse 100 opening, and all of these openings intersect each other intermediate their ends. The object of this type of intersecting openings is to always present a pocket beneath the point of intersection so that if an attempt is 105 made to force a wire through the openings the probabilities are that the wire will extend into one of the pockets and that it will be finally lodged in such manner that it will be impossible to force the wire any farther.

110

Having thus described my invention, what I desire to claim is:—

In a device of the class described in combination with a bottle neck, a tubular member provided with a flange upon the upper end thereof, a circumferential bead formed on said tubular member, a ball within said tubular member co-operating with said bead to form a valve, a packing ring lying within the groove which said bead forms upon the exterior of said tubular member, and a barrier above said valve.
